UNITED STATES PATENT OFFICE.

SIDNEY L. LONG, OF MINNEAPOLIS, MINNESOTA.

COIN-CONTROLLED VENDING-MACHINE.

No. 831,169.

Specification of Letters Patent.

Patented Sept. 18, 1906.

Application filed May 29, 1905. Serial No. 262,734.

To all whom it may concern:

Be it known that I, SIDNEY L. LONG, a citizen of the United States, residing at Minneapolis, in the county of Hennepin and State of Minnesota, have invented certain new and useful Improvements in Coin-Controlled Vending-Machines; and I do hereby declare the following to be a full, clear, and exact description of the invention, such as will enable others skilled in the art to which it appertains to make and use the same.

My invention relates to coin-controlled vending-machines, and has for its especial object to provide a machine in which different kinds of articles may be sold under the control of a single coin mechanism.

To the above ends the invention consists of the novel devices and combinations of devices hereinafter described, and defined in the claims.

In the accompanying drawings, which illustrate my invention, like characters indicate like parts throughout the several views.

Referring to the drawings, Figure 1 is a view in front elevation with some parts broken away and with some sectioned, illustrating a vending-machine having embodied therein the several features of my invention.

Fig. 2 is a vertical section taken through the machine approximately on the line $x^1 x^2$ of Fig. 1. Fig. 3 is a vertical section taken through the machine approximately on the line $x^3 x^3$ of Fig. 1; and Figs. 4 and 5 are detail views, in horizontal section, on the line x^4 of Fig. 1, illustrating different positions of the parts.

The numeral 1 indicates a vertically-elongated case, the lower portion of which is expanded from front to rear to afford a shelf 2 and to afford a compartment of sufficient size to contain all of the operative parts of the mechanism. Set into the vertical front wall of the case above the shelf 2 is a glass pane 3. Rigidly secured side by side within the upper portion of the case and depending into the enlarged lower compartment thereof is a plurality of upright magazines or holders 4, that are open at their upper ends and are preferably also partially open at their front faces, as best shown in Fig. 1. At their lower ends these magazines are open and are provided with depending side plates 4^a, formed with inturned box-supporting flanges 4^b. The articles to be sold are preferably put up in packages, such as boxes 2, and which boxes or packages loosely fit within said magazines

and the lower members of which normally rest upon the said box-supporting flanges 4^b just noted. The lower boxes are thus supported by the flanges 4^b in such manner that they may be discharged from said magazine only by forward movements, which forward movements are accomplished by means of so-called "ejectors." These ejectors, of which there is one for each magazine, are preferably in the form of segments 5, that are loosely and independently mounted on a rock-shaft 6, loosely journaled in bearing-brackets 7 and 8, rigidly secured within the enlarged lower compartment of the case 1. Each ejector 5 is provided with a depending leg 9 for a purpose which will presently appear.

For operating the ejectors—that is, for moving the same from their normal position (indicated by full lines in Fig. 2) into their discharging positions (indicated by dotted lines in said Fig. 2)—I provide key mechanism preferably comprising vertically-moving keys 10, links 11, and levers 12. The stem of the keys 10 work through the shelf 2 of the case 1, and the links 11 pivotally connect the lower ends of said stems to the forward ends of the levers 12. The levers 12 are pivoted at 12^a to the ejectors 5, and their rearwardly-projecting ends normally engage with the rear edges of the segmental ends of the said ejectors. With this construction downward pressure on the keys 10 positively forces the corresponding ejector from its normal position into its ejection position, (assuming, of course, that the said ejector is not locked against such movement,) but an upward movement of said stems will have no tendency whatever to return the said ejectors to their normal positions. The rearward movements of the ejectors are limited by stops 13, secured to the back plate of the case. The ejectors 5 are preferably mounted on the shafts 6 for quite free movements, but under sufficient friction to prevent either accidental or untimely movements, so that they will tend to stand in whatever positions they may be set. To normally lock all of the ejectors against operative movements, I provide what I term a "primary" lock device. This primary lock device when released will permit any one of the ejectors to be given its operative movement. As a means for permitting the movement of any one of the ejectors when released by the primary lock device, but for preventing the movement of more than one actuator, I provide what I

herein term a "secondary" or "limiting" lock. The primary lock device, which is common to all of the ejectors, is arranged to be released by a single coin mechanism and by the deposit of a single coin. The primary lock device, as shown, includes stub-arms 15, that are rigidly secured on the rock-shaft 6, one adjacent to each ejector 5, each of said arms having laterally-projecting stop-lugs 16, that project in front of the respective ejectors and with which said ejectors engage. On the right-hand end of the rock-shaft 6 as viewed in Fig. 1 is rigidly secured a four-armed lever 17, 18, 19, and 20. A quite strong coiled spring 21, secured to the short arm 20 and to one of a pair of stud-lock projections 22 on the bracket 7, normally holds the arm 18 against a stop 23 on said bracket 7. This spring 21 has such strength that it readily overcomes all of the light springs 14, and hence normally holds the parts carried by the shaft 6 and also the ejectors in the position indicated by full lines in the drawings. A lock-dog 24 is pivoted to the arm 17 and normally stands with its free end in position to engage the stop 23 above noted. A forwardly-projecting trip-arm 25 is rigidly secured to the lock-dog 24 and at its free forward end is provided with a trough-like coin-receptacle 26. A light coiled spring 27, attached to the trip-arm 25 and to the arm 19, normally holds the parts 24, 25, and 26 in the positions indicated by full lines in Fig. 3. To the free end of the arm 18 is pivoted a toggle-acting retaining-dog 28, which is yieldingly held by a spring 29 in the extended position. (Shown in Fig. 3.) On the upper portion of the bearing-bracket 7 is a segmental ratchet-bar 30, that is so located that when the arm 18 is moved forward the retaining-dog 28 will be moved pivotally backward and will engage the ratchet-teeth and prevent a return movement of said arm, and hence of the rock-shaft 6 and other parts carried thereby, unless the said arm be first moved far enough to carry the free end of said retaining-dog forward of and out of engagement with said ratchet-bar 30, whereupon under a return movement of said arm said retaining-dog will be moved pivotally and permit the return movement of said arm.

In the drawings the coin is indicated both by full and dotted lines and is marked by the character z' . This coin is adapted to be inserted into the case through a delivery-spout 31, the upper end of which opens through the shelf 2. From the spout 31 the coin drops into a second spout 32, located within the case with its lower end in position to direct the coin directly into the coin-receptacle 26 on the free end of the trip-arm 25.

The numeral 33 indicates a coin-detainer in the form of a metallic strip secured to and projecting laterally from the bracket 7 and located in position to hold the coin within

the receptacle 26 when said receptacle is moved downward into the position indicated by dotted lines in Fig. 3.

The numeral 34 indicates a magnet secured to the bracket 7 in position to catch and hold iron slugs in case the same should be inserted into the machine instead of a coin. This magnet forms no part of my present invention.

The secondary or limiting lock mechanism 75 operates upon the depending legs 9 of the ejectors 5 and, as shown, comprise a pair of sliding lock-plates 35, that are mounted for sliding movements in a channeled support 36, rigidly secured to the bottom of the case 80 1. At their forward edges, in line with the several ejector-legs 9, the limiting-plates 35 are beveled at 35° . The limiting-plates 35 are of such width and are so related to the ejector-legs 9 that any one, but only one of 85 the said legs, may be moved rearward under an operative movement of its ejector. Such rearward movement of one of the legs 9 will either produce a separation of the two plates 35, as shown in Fig. 4, or will cause the said 90 plates to move together, as shown in Fig. 5, and thereby lock against rearward movements the other two legs 9 and the corresponding ejectors. This construction of 95 course permits the use of any desired number of ejectors in connection with a single coin-actuated releasing device. The bearing 36 is of course cut away, so as to permit free rearward movements of the legs 9 of the several ejectors.

The numeral 37 indicates a hopper secured within the case in position to receive the boxes or articles z which are discharged from the magazines by the ejectors. An opening 38 in the front of the case 1 close to the bottom thereof opens into the bottom of the hopper 37, so that the box deposited therein may be reached with the fingers and removed from the case by the purchaser.

The characters y , y' , and y'' indicate sample 110 articles placed within the case back of the pane 3 to indicate the class of articles contained in the several magazines. The said articles, as illustrated, are collar and cuff buttons.

The operation is probably obvious from the foregoing description, but may be briefly summarized as follows: The purchaser deposits a coin in the upper end of the spout 31, and this coin, as already described, is deposited in the receptacle 26 on the free end of the trip-arm 17. The coin thus deposited on the receptacle 26 by its weight overcomes the light spring 27 and forces the lock-dog 24 against the stop-arm 19, as indicated by dotted lines in Fig. 3. In this dotted-line position the lock-dog 24 stands in the position in which it will clear the stop 23 under an oscillatory movement of the rock-shaft 6. Thus it will be seen that the primary lock device is 130

released by the weight of the deposited coin. So far as the primary lock device is concerned all of the actuators are then released, and any one of the actuators may be given an operative or ejecting movement by pressing downward on its connected key 10, thereby forcing the ejector into the dotted-line position shown in Fig. 2 and ejecting one of the boxes or articles ^z from the corresponding magazine. The secondary or limiting lock then comes into play to prevent the depression of the second key and the movement of a second actuator until after the movable parts of the primary lock device have been restored to normal position and again released by the deposit of another coin. The retaining-dog 28 and ratchet-bar 30, as already described, prevent a return movement of the rock-shaft 6 and parts carried thereby from any intermediate position and permit such return movement only after the said rock-shaft has been given its extreme movement and has carried the said dog 28 forward of said ratchet-bar. This extreme movement of the rock-shaft under extreme downward movement of one of the keys 10 carries the coin-receptacle 26 sufficiently far below the position indicated by dotted lines in Fig. 3 and below the detainer or stop 33 to permit the coin to drop therefrom onto the bottom of the case or into some receptacle (not shown) which might be provided to receive the same. As soon as the depressed key is released the spring 21 immediately throws the rock-shaft 35 and parts carried thereby back into their normal positions, under which movement the ejector which was just operated is forced positively backward to its normal position by the engagement of the corresponding stop-lug 16 therewith.

In my experiment with machines of this general character I found that when the keys were so connected to the respective ejectors that they could impart movements thereto in both directions it was sometimes possible to force the key down far enough to cause the ejector to dislodge one of the parcels ^z without carrying the retaining-pawl 28 out of engagement with the forward end of the ratchet-bar 30 and then by repeated manipulations of said key discharge in succession a plurality of the said parcels. This action or "cheating" of the machine is prevented in my improved machine by an arrangement which permits the key to be raised without returning to normal position the corresponding ejector 5. The springs 14 serve to prevent the said ejectors from being accidentally jarred or moved to normal positions by upward movements of the keys 10. The said springs are of course of such light tension that they will be overcome by springs 21 when the retaining-pawl 28 has been forced forward of the ratchet-bar 30.

From what has been said it will of course

be understood that any desired number of magazines or holders and operating-ejectors may be employed in connection with a single coin-actuated lock-releasing mechanism.

I believe that I am the first to arrange a single coin-actuated lock-releasing device in combination with a plurality of magazines or article-supplying devices and co-operating positively-acting ejectors and desire to claim this feature from the broadest point of view. From what has been said it of course follows that the mechanism illustrated in the drawings is capable of large range of modification within the scope of my invention as herein set forth and claimed.

The term "magazines" is used in a broad sense to include means for holding the articles to be vended or delivered from the machine. The term "ejectors" is used in a broad sense to include means for effecting the delivery of the articles from the magazines. The term "coin" is used in a broad sense to include all devices by the deposit of which the trip is actuated to release the lock mechanism.

What I claim, and desire to secure by Letters Patent of the United States, is as follows:

1. In a vending-machine, the combination with a plurality of magazines and a plurality of positively-acting ejectors, of limiting lock mechanism permitting the movement of any one of said ejectors, and preventing the movement of the others, means for releasing said ejectors by the deposit of a coin, and means for positively operating any one of the released ejectors, substantially as described.

2. In a vending-machine, the combination with a plurality of magazines and a plurality of ejectors, of key connections to said ejectors arranged to impart operative movements thereto, a primary lock device operative to simultaneously lock and simultaneously release all of said actuators, a secondary or limiting lock operating to permit the movement of any one of said ejectors and preventing the movement of the others, and a coin-actuated releasing device for said primary lock, substantially as described.

3. In a vending-machine, the combination with a plurality of magazines and a plurality of ejectors, of key connections to said ejectors, arranged to impart positive operative movements thereto, but themselves capable of movements back to normal position while said actuators are in set positions, substantially as described.

4. In a vending-machine, the combination with a plurality of magazines, of a rock-shaft below said magazines, a plurality of ejectors loosely pivoted on said rock-shaft and co-operating with said magazines, stops carried by said rock-shaft and normally holding said ejectors in inoperative positions, a lock-dog normally holding said rock-shaft against

movement, means whereby a deposited coin will cause said dog to release said shaft and parts carried thereby, and a secondary or limiting lock, permitting the movement of one, but only one of said actuators, substantially as described.

5. In a vending-machine, the combination with a plurality of ejectors, of a rock-shaft on which said ejectors are independently pivot-
10 ed, stops carried by said rock-shaft and normally holding said ejectors in inoperative positions, a spring yieldingly holding said rock-shaft and parts carried thereby in a normal position, a lock-dog pivoted on a projection
15 carried by said rock-shaft, a fixed stop coöperating with said lock-dog to normally lock

said rock-shaft, a spring-held arm attached to said lock-dog and provided with a coin-receptacle, means for directing the coin into said coin-receptacle, key connections for imparting operative movements to said actuators, and a secondary lock device operating to permit the movement of one, but only of one of said actuators, substantially as described. 20

25 In testimony whereof I affix my signature in presence of two witnesses.
